NURSING BOTTLE HOLDER

Stuart F. Faunce, Norman, Okla.

Application March 29, 1954, Serial No. 419,246

2 Claims. (Cl. 248—106)

The present invention relates to a nursing bottle holder and particularly to such a device which is capable of being readily folded for movement and storage.

One of the most time consuming chores of the busy mother is that of bottle feeding her small child. There has been wanting a relatively "foolproof" device for supporting the nursing bottle during these feeding periods, thereby permitting the mother to leave the child unattended, while nursing, and go about her other chores. Such a device, in order to be satisfactory, should embody the following features:

The bottle should be held in such a manner that the nipple fits naturally into the baby's mouth;

The bottle should be held in such a manner as to permit slight movement thereof, in response to the movement of the baby's lips, in order to minimize the amount of air which will be swallowed by the baby;

The device should be adaptable to support most types of nursing bottles;

The bottle should be so supported that the nipple will come out of the baby's mouth in case he coughs or stops nursing;

The device should be such as to permit the baby to kick and flail his arms about, while nursing, without upsetting the device;

The device should be capable of adjustment to permit its use while the baby lies in its bed, bassinet, buggy, or on a table or other flat surfaces;

The device should be easily set up and taken down without dismantling; and

There should be nothing about the device which might cause harm to the baby, such as sharp corners or projections, or the like.

The primary object of this invention is to provide a device for supporting a nursing bottle which will include all the features and functional advantages set forth above.

A further object is to provide such a device having the above stated features which will be relatively simple and inexpensive to manufacture.

Further objects will become apparent as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a pictorial view showing my invention in its position of intended use;

Fig. 2 is an enlarged perspective view, partially in section, showing a detail of construction;

Fig. 3 is an enlarged perspective view, partially in section, showing a further detail of construction; and

Fig. 4 is a perspective view, showing the manner in which the device can be folded for transportation or storage.

2

Referring more particularly to the drawings, and especially to Fig. 1, it will be seen that my device comprises a frame in the form of a tripod, referred to generally by the reference numeral 10, and comprising a trio of leg members 11. Such leg members are preferably in the form of relatively rigid rods and are connected together at one end by means of a rubberoid disc 12. Said disc is provided with a trio of passages 13 substantially equiangularly spaced therein and one end of each of the rods 11 is formed with a reduced portion 14 for insertion through one of said passages. The ends of said rods are then headed as at 15 to fix the rods securely to disc 12. Thus, it will be seen, that the legs 11 of the tripod 10 are free to be spread apart any amount desirable, 15 by flexure of the disc 12.

In order to control the degree of spread of the legs 11, I provide a spider element, indicated generally by the reference numeral 16, and comprising an annulus 17 preferably formed of a rubberoid material. Said annulus 20 is provided, preferably integrally therewith, with a trio of arms 18 extending radially therefrom and spaced substantially 120° apart. Eyelets 19 are preferably integrally formed at the distal ends of arms 18. A leg member 11 is snugly received through each of eyelets 19 permitting 25 the spider 16 to be moved readily up or down leg members 11 to vary the degree of spread of such leg members.

Within annulus 17, I provide a relatively rigid disc or plate 20 here shown as being securely supported in annulus 17 by means of the tongue and groove arrangement 21. Plate 20 is provided with an aperture 22 and with a slot 23 extending radially therefrom.

A flexible strand member 24, here shown as comprising a length of ball-chain 25 and an elastic cord 26, is supported from plate 20. The diameter of the balls of chain 25 is small enough to pass through the aperture 22 but too large to pass through the slot 23. The effective length of the strand 24 can, thereby, be varied by shifting the chain 25 through aperture 22 and then moving the chain laterally into slot 23.

40 An elastic ring 27 is preferably integrally formed in the distal end of cord 26. A nursing bottle 28, of any cross-sectional contour, can be slipped through ring 27 and will be held frictionally therein by said ring member. I have found that by positioning ring member 27 approximately one-third of the distance from the bottom of the bottle to the top of the bottle, the bottle will be supported in the proper position for feeding a child lying beneath the tripod 10.

45 In use, a baby is placed upon a suitable surface and the spider element 16 is then adjusted along legs 11 to spread the legs sufficiently to straddle the child. The bottle 28 is then inserted through ring 27, as described above, and the length of the strand 24 is then adjusted so that the nipple on the bottle will remain in the baby's 50 mouth while the baby is nursing, but will pull away from the baby's mouth should he cough or stop nursing for any reason. The provision of the elastic cord 26 permits the bottle 28 to move in response to movement of the baby's lips, thereby minimizing the amount of air which 55 will be sucked into the baby's mouth and swallowed by him.

Where a child is particularly active and likely to move about while feeding, it is sometimes necessary to provide additional means to prevent tipping of tripod 10 in 60 case the child moves against one of the legs 11. To this end, I provide the spider element 29 formed of any suitable, soft, relatively flexible material, such as sheet rubber or fabric, and having provided, in the end of each of the arms 30 thereof, a socket 31. The ends of the rods 11 are inserted in sockets 31 in setting up the device. A 65 blanket or the like is then spread over the spider 29

and the child is placed thereon. I have found that such an arrangement is very effective in preventing accidental tipping of tripod 10. When the spider 29 is not used rubber tips 32 are placed on the lower ends of legs 11.

When it is desirable to fold the device for transportation or storage, the eyelets 19 are moved up and down the respective leg members 11 to permit the leg members to be moved into substantial parallelism as clearly illustrated in Fig. 4. Prior to this however, the strand 24 is removed from spider 16. The ring member 27 is then 10 slipped over the lower ends of the legs 11 and the cord 26 and chain 25 are wound about the legs with the end of the chain 25 being tucked through the ring 27. The legs are thus held securely in their folded position and the device presents a neat compact package.

I claim as my invention:

1. In a device of the class described, a tripod comprising a trio of leg members, a rubberoid disc having a trio of passages formed therein substantially 120° apart, one end of each of said leg members being inserted through 20 one of said passages and fixed therein to permit spreading apart of the other ends of said leg members, and a plate member supporting a trio of elastic eyelets at points spaced substantially 120° about the periphery thereof, each of said leg members being snugly received through 25 one of said eyelets and gripped thereby to support said plate member between said trio of leg members, said eyelets being axially slidably adjustable thereon to permit the degree of spread of said leg members to be varied.

2. A nursing bottle holder comprising a trio of leg 30 members, an elastically-flexible disc of rubberoid material formed to provide a plurality of separate sockets at angularly spaced points, each of said leg members having an end engaged in one of said sockets whereby said leg member ends are connected together and the opposite

5 ends of said leg members may be spread apart with corresponding flexure of said disc, a plate member supporting a trio of elastic eyelets of rubberoid material at points angularly spaced about the periphery thereof, said leg members each being snugly received through one of said eyelets and gripped thereby to support said plate member, said eyelets being axially slidably adjustable along said leg members to permit the degree of spread of said opposite ends of said leg members to be varied, a flexible strand member supported from said plate member, and an endless elastic ring member supported from said strand member and frictionally engageable with a nursing bottle inserted through said ring member.
